UNITED STATES PATENT OFFICE

EDWARD JOSEPH PAVELKA, OF NEW YORK, N. Y.

REFUSE RECEPTACLE

Application filed August 17, 1929. Serial No. 386,656.

This invention relates to a refuse receptacle in combination with a closure construction such as a storm door of a dwelling.

The principal object of the invention is the provision of a combination of the indicated character whereby refuse may be deposited into the receptacle from the inside of the closure without opening the latter, and therefore without allowing elements of the weather, such as rain and snow, to enter a room or apartment of a dwelling.

The nature of the invention and its distinguishing features and advantages will appear when the following specification is read in connection with the accompanying drawings, in which—

Figure 1 is a vertical section of a storm closure construction, together with a refuse receptacle, its support, and the closure opening and receptacle cover, the parts of the latter being shown in closed positions, the section indicated by the line 1—1 of Fig. 2.

Fig. 2 is an outside view of the lower part of the closure or storm door and parts associated therewith.

Fig. 3 is a vertical section taken on the line 3—3 of Fig. 2, but showing the parts of the cover in opened positions.

Fig. 4 is a view similar to Fig. 3, but showing the cover part for the closure or door opening in the closed position, and the cover part for the receptacle in the opened position.

In the illustrated embodiment of the invention, there is shown a storm closure construction which consists of a frame structure 10 whose opening is controlled by an inner closure member or door 11 and an outer closure member or storm door 12. The door 12 has an opening 13 located centrally thereof near the bottom. A suitable support or holder 14 is fixedly secured to the door 12 directly below the opening 13 therein. The support or holder 14 is adapted to support or hold a refuse receptacle 15. The receptacle 15 will be of such size that when placed in the support or holder 14 will be in a position to receive refuse from the inside of the door 12 through the opening 13. A cover consisting of parts 16 and 17 is provided, the parts 16

and 17 being hingedly connected together as at 18, and the part 16 being hingedly connected as at 19 with the door 12 at the top of the opening 13. The part 16 of the cover serves for closing the opening 13 in the door 12, and the part 17 of the cover serves for closing the receptacle 15. By reason of the construction of the cover and the manner in which it is mounted or suspended on the door 12 makes it possible to move the parts of the cover by a force applied to the part 16, to opened position, simultaneously, as shown in Fig. 3, for the purpose of introducing the refuse into the receptacle 15.

In order to hold the cover part 16 in a closed position, means is provided consisting of a latch 20 secured to the part 16, and a keeper 21 secured to the door 12, with which the latch 20 cooperates. The latch 20 may be readily disengaged from the keeper to enable the cover parts to be swung or pushed outwardly to the opened position. When the force applied to the part 16 to move the cover parts to the opened position is withdrawn, the cover parts will swing to the closed positions. Although the part 16 of the cover is latched, the part 17 may be raised from its closed position, to an opened position, to allow the removal of the receptacle 15, as shown most clearly in Fig. 4.

From the foregoing it will be apparent that refuse may be deposited into the receptacle 15 from the inside of the door 12 without opening the latter, and therefore without allowing elements of the weather, such as rain or snow, to beat into a room or apartment.

It is to be understood that the cover instead of being made of two parts hingedly connected together may consist of one part of angular construction to control both the opening 13 in the door 12 and the receptacle 15 to cover and uncover the latter.

It is further to be understood that the invention is not restricted to the precise arrangement of parts shown and described, as details of construction may be modified and rearranged without departing from the spirit of the invention, the scope of which is limited only by the terms of the appended claims.

I claim:

1. The combination with a closure having an opening therein, of a removable receptacle, a support on said closure for supporting said receptacle below said opening, a cover for said receptacle, and means connecting said cover with said closure for movement to open and close said receptacle.
2. The combination with a closure having an opening therein, of a removable receptacle, a support on said closure for supporting said receptacle below said opening, a cover for said opening and receptacle, and means connecting said cover with said closure for movement to uncover said opening and receptacle, for the purpose of introducing matter into said receptacle.
3. The combination with a closure having an opening therein, of a removable receptacle, a support on said closure for supporting said receptacle below said opening, a cover for said receptacle, means connecting said cover with said closure for movement to open and close said receptacle, said cover being movable to open said receptacle by a force applied to said cover, and said cover being self-movable to close said receptacle.
4. The combination with a closure having an opening therein, of a removable receptacle, a support on said closure for supporting said receptacle below said opening, a cover for said receptacle, means connecting said cover with said closure for movement to open and close said receptacle, and means to latch said cover in the closed position.
5. The combination with a closure having an opening therein, of a receptacle, a support on said closure for supporting said receptacle below said opening, a cover consisting of hingedly connected parts for said opening and receptacle, and means connecting said cover with said closure over said opening for swinging movement, whereby the parts of said cover will open and close said opening and receptacle.
6. The combination with a closure having an opening therein, of a receptacle, a support on said closure for supporting said receptacle below said opening, a cover for said opening hingedly suspended from said closure, and a cover for said receptacle hingedly connected with said first cover, both the opening in the closure and the opening in said receptacle being uncovered by movement of said first cover, and said receptacle cover being movable alone to uncover the receptacle.
7. The combination with a closure having an opening therein, of a receptacle, a support on said closure for supporting said receptacle below said opening, a cover for said opening hingedly suspended from said closure, and a cover for said receptacle hingedly connected with said first cover, both the opening in the closure and the opening in

said receptacle being uncovered by movement of said first cover, a keeper on said closure, and a latch on said first cover engageable with said keeper to latch said covers in closed positions.

Signed at 2162 Paulding Ave, in the county of Bronx and State of New York this 14th day of August, A. D. 1929.

EDWARD JOSEPH PAVELKA.
